UNITED STATES PATENT OFFICE.

ELROY A. CHASE, OF WORCESTER, MASSACHUSETTS, ASSIGNOR TO AMERICAN
GRANITE SAW COMPANY, A CORPORATION OF MAINE.

METHOD OF CUTTING STONE.

1,095,707.

Specification of Letters Patent.

Patented May 5, 1914.

Application filed April 28, 1910. Serial No. 558,236.

To all whom it may concern:

Be it known that I, ELROY A. CHASE, a citizen of the United States, residing at Worcester, in the county of Worcester and 5 State of Massachusetts, have invented a new and useful Method of Cutting Stone, of which the following is a specification.

This invention relates to a new method of cutting stone. The method consists in successively making a series of directly intersecting curved kerfs in alinement in the stone preferably in relative lower location. The instrumentality preferably used is a series of alined vibrating cutters. Abrasive 15 material is supplied so that it will wedge back and forth under the ends of said cutters gradually down from one kerf to another, and thus gradually out of the slot which is sawed in the stone. The abrasive 20 material is taken after it has been used in this manner and put back into operative position preferably in the first kerf.

Many different forms of apparatus may be devised for practising the invention. 25 In the drawings, Figure 1 is a sectional elevation showing the essential parts of an apparatus arranged to practise the method; Fig. 2 is a sectional view on enlarged scale; and Figs. 3, 4 and 5 are diagrammatic views 30 illustrating the way the method is practised.

The apparatus will first be referred to.

In the drawings A designates a series of cutter carrying heads which are mounted on pivots B. The line of pivots is preferably inclined as shown. The upper ends of the cutter heads are connected together by a link C, each cutter being journaled to the link by a pin D.

E designates a power-driven shaft carrying a crank or wrist-plate F which has a wrist-pin G which connects by a pitman H to a pin I carried by the link C. By this arrangement the cutter heads will be vibrated back and forth synchronously on their pivots. Cutters J are secured in the cutter heads. These cutters consist of flat blades or pieces of steel, the ends of which are preferably curved or shaped to coincide with the arcs described by the ends of the cutters. The lower ends of the cutter-heads are preferably arranged in about the same horizontal line, but the cutters are made successively longer as shown, so that their cutting ends will be on an inclined line

preferably parallel to line of pivots B. The 55 cutters and stone are arranged so that a relative feed movement may be effected between the same. This can be done by feeding either the cutters or the stone, but it is preferred in most instances to feed the stone. 60 To this end K designates a car or carrier, the wheels of which run on preferably horizontal rails. Any suitable feeding device as a screw and nut or gearing is arranged to move the carriage or car relatively to the 65 cutters. The stone is held on the car and blocks L are preferably arranged on the car as shown in Fig. 2, so that the last cutter can go entirely through the stone. Troughs or partitions M are arranged in the car be- 70 tween the wheels thereof to direct the emerging abrasive material clear of the car laterally.

In operation the stone is placed on the car and the car moved toward the back of 75 the machine until cutter No. 1 engages the stone. Then the feed is put on and abrasive material is supplied under this cutter. As the stone moves under blade No. 1 a curved kerf will be cut therein. The stone then 80 engages cutter No. 2 and a second curved kerf will be cut therein vertically below the kerf made by cutter No. 1. This operation will be repeated with each cutter. In this way the stone will be sawed through vertically, the 85 kerfs thus being made successively through the stone as indicated at the left in Fig. 3.

It will be seen that the curved kerfs or cuts will intersect each other and that when the stone is engaged by all the cutters that all 90 the various kerfs will be made simultaneously through the stone by the action of the cutters and the feed.

Abrasive material is supplied preferably 95 in the first kerf. This abrasive material will be presented with a peculiar crushing or wedging effect and will work back and forth under the ends of the cutters and gradually down out through the slot cut in the stone. As the stone progresses under the cutters the 100 abrasive material will run out sidewise or laterally on the troughs M and will be shoveled or taken and put back in the first kerf. Boards or other devices N are provided so that the abrasive material can be 105 easily applied in the slot.

The abrasive material which is used preferably consists of small hardened steel shot.

The peculiar crushing effect which is obtained by the cutters is illustrated by the diagrams.

In Fig. 3 the cutters are shown in their extreme forward position. As the cutters swing from the forward position through the intermediate position shown in Fig. 4 to the rearward position shown in Fig. 5 the abrasive material in any particular kerf will be forced by the cutter working in that kerf under the next succeeding cutter, both by the action of said cutter and by gravity. This provides for a wedging action of the abrasive material under the end of each cutter which causes the cutters to work with a great deal of force on the points where the kerfs intersect, which are the points of greatest resistance or of hardest work.

On the backward stroke of the cutters the abrasive material will also be forced between the ends of the cutters and the points of intersection of the kerfs. This will also force the abrasive material back under the ends of the cutters with this peculiar wedging effect, so that on this stroke the cutters will work with a crushing effect on the points of intersection of the curved kerfs. As the abrasive material is not forced forwardly as powerfully as it is forced backwardly by the said action, the abrasive material will gradually work down through the slot and out of the stone under the last cutter.

The method can be practised very economically as cars may be sent through the machine in succession so that all the cutters will be working after they have once been started into the stone.

Many different forms of apparatus may be devised for practising the invention without departing from the method herein claimed.

Having thus fully described my invention, what I claim is:—

1. The method of cutting stone which consists in successively making a series of directly intersecting curved kerfs in alinement therein and in gradually changing the relative longitudinal position of said kerfs in said stone.

2. The method of cutting stone which consists in successively making a series of directly intersecting curved kerfs in alinement therein in relative lower location.

3. The method of cutting stone which consists in successively making a number of

curved kerfs in alinement therein by a series of alined vibrating cutters, and supplying abrasive material thereto, so that it will wedge back and forth under the ends of 60 said cutters.

4. The method of cutting stone, which consists in successively making a series of directly intersecting arc-shaped kerfs in alinement therein and in simultaneously and progressively changing the relative longitudinal location of said kerfs in said stone. 65

5. The method of cutting stone which consists in successively making a series of intersecting curved kerfs in alinement therein by a series of alined vibrating cutters, and supplying abrasive material thereto so that it will wedge back and forth under the ends of said cutters. 70

6. The method of cutting stone which 75 consists in successively making a series of curved kerfs in alinement therein in relative lower order by a series of alined vibrating cutters, and supplying abrasive material at the first kerf so that it will wedge back and 80 forth under the ends of said cutters and will work gradually down from one kerf to another.

7. The method of cutting stone which 85 consists in successively making a series of intersecting curved kerfs in alinement therein in relatively lower location by a series of alined vibrating cutters, and supplying abrasive material to the slot formed by said kerfs near the first kerf so that it will 90 wedge back and forth under the ends of said cutters and will work gradually out of said slot.

8. The method of cutting stone which 95 consists in successively making a series of intersecting curved kerfs in alinement therein in relative lower location by a series of alined vibrating cutters, supplying abrasive material to the slot formed by said kerfs near the first kerf so that it will wedge back 100 and forth under the ends of said cutters and will work gradually out of said slot, and taking said abrasive material after it has thus worked out and supplying the same again near the first kerf. 105

In testimony whereof I have hereunto set my hand, in the presence of two subscribing witnesses.

ELROY A. CHASE.
